METHOD OF PREPARATION OF DENTAL
PROSTHETIC DEVICES

Duncan S. McPhee, Seattle, Wash.

Application March 27, 1951, Serial No. 217,759

6 Claims. (Cl. 32—2)

1

My invention relates to an improved method of preparation of dental prosthetic devices and, more particularly, relates to a method of determining the inclination of a patient's plane of occlusion relative the horizontal and of establishing that inclination in the models when they are positioned in an articulator.

This application is a continuation in part of my application, Serial No. 148,128, filed March 7, 1950, now Patent No. 2,621,406.

In the preparation of dental prosthetic devices that are fully useful, life-like, pleasing and comfortable to the patient, and which function properly in the mouth of the patient, it is necessary that the dentist know as much as possible about the characteristics of the patient's jaw. While much can be determined from observation, many of the particular characteristics are blurred or indeterminable when the patient's natural teeth have been extracted. Then the maxilla and mandible have a relation that is largely one of irregular space therebetween and often the actual frontal dimensions lost or indeterminable by conventional methods. Such conditions particularly complicate the establishment in an articulator of the models of the upper and lower jaws that are normally formed according to conventional practices.

I have found that if the lateral inclination, if any, that exists in the maxilla relative the horizontal can be accurately determined by means of a bite-plate in the mouth, such lateral inclination can be established in the articulator with considerable speed and a very high degree of accuracy. Having established the location or aspect of the maxilla model, it becomes very simple thereafter to establish in the articulator, the corresponding aspect of the mandible relative the maxilla in the relation thereto found in the patient's mouth. Then, according to other improved techniques that I have developed, the dentist may proceed with confidence that he will simply and accurately prepare dentures which will be comfortable and will function properly when applied to the mouth. In fact, such success has been enjoyed with the process disclosed that seldom, if ever, is it necessary to perform any more than the slightest of post-fitting adjustments between dentures or with regard to their fit on the jaws in the relief of undesirable or harmful pressures.

Among the important objects of my invention, therefore, is to provide a simple and accurate method of determining lateral inclinations of a patient's jaw in such manner that such determination can be readily reproduced in an articu-

2

lator as an aid in the mounting of the models in faithful correspondence to nature and to add to the comfort and suitability of the dentures for mastication and aesthetic purposes; to provide a process for producing an accurate determination of maxilla aspect, through use of a maxilla bite-plate, and for transferring that aspect into an articulator; and to devise a method of adjusting the models in an articulator to obtain a proper division of the intermaxillary space while providing a desirable plane of occlusion, whereby dentures produced will properly distribute the grinding pressures of mastication to favor or disfavor bone conditions found in the jaws of the patient.

It will be apparent that these objects are of a general nature and it is pointed out that these and other objects will be more apparent from reading the following description specifying the techniques and apparatus employed in carrying out my process, reference being made to the accompanying drawings showing a specific embodiment of apparatus adapted for use in the preparation of dentures by my method. It is to be understood, however, that certain variations in the method described may be made by those skilled in the art without departing from the scope of the invention as exemplified by the accompanying claims.

In the drawings:

Figure 1 is a side view of a Fournet type articulator including certain appliances which I have developed and showing a maxilla bite-plate and model positioned on a bite-table;

Figure 2 is a side view of the articulator with portions broken away for convenience of illustration and showing upper and lower models and bite-plates in position therein;

Figure 3 is a perspective view of the bite-table and bite-plate showing in detail the bite-table levelling means;

Figure 4 is a perspective view of the spiling means employed in scribing a line on a model; and

Figure 5 is an enlarged perspective view, in exploded and fragmentary form, showing the bite-table and its supporting assembly.

Preparation of bite plates

In the practice of my invention, I employ the customary techniques in the preparation of upper bite-plate 10 and lower bite-plate 12 which fit models of the maxilla and mandible of the patient, 14 and 16 respectively. As is well known to those skilled in the art, a plastic female impression is first taken of the patient's jaw; and

from this is molded, by casting therein, plaster models of upper and lower jaws, as 14 and 16, on which the denture will be constructed. Following the preparation of models 14, 16, bite-plates 10, 12 are molded in conventional manner in the models. The interior recesses of bite-plates 10, 12 accurately fit the patient's jaw and may be placed thereon as desired by the dentist, for example as in applying line 17 (Figure 3) which corresponds to the median line of the face. I prefer to form the lower portions of the bite-plate with a substantially broad, flat surface, as 11 in Figure 3, in order that it may be mounted securely on bite-table 18, to which it is secured with line 17 coinciding with fore-and-aft median 19 of the bite-table. The bite-plate is secured to the bite-table by the application of wax adhesive 20 shown in Figure 3.

The bite table and supporting assembly

In the determination of the lateral aspect of the patient's jaw relative horizontal, upper bite-plate 10 is secured to bite-table 18, as shown in Figure 3 with median lines 17 and 19 coinciding. Upper bite-plate 10 is placed in the patient's mouth with the bite-plate firmly seated on the maxilla. At that time, arm 22 will extend forwardly of the mouth between the patient's lips. On arm 22 is lateral arm 24 which provides the support for spirit level 26 that is rockably mounted on the generally horizontal screw pivot 28. It will be noted that by this arrangement spirit level 26 is arranged to rock in an upright plane that is parallel to a similar upright plane passing laterally through the patient's jaw. With the patient's head in a vertical position, whenever the spirit level is located in that plane and oriented so that the bubble is centered in the tube, a determination of the aspect of the patient's jaw laterally with respect to the horizontal will be established. When the bite-table and bite-plate are removed from the mouth and subsequently mounted on a support and the spirit level is again placed with the bubble centered, bite-plate 10 will be located laterally in exactly the same position with relation to the horizontal that it occupied in the mouth.

For convenience of operation in the leveling of spirit level 26 and in order to maintain relative adjustments of spirit level 26 to bite-table 18 during such transfer and mounting, I provide manually operable adjusting and securing means between the spirit level and supporting arm 22 of the bite-table. The means is shown in Figure 3 and comprises bearing block 30 in which is rotatably mounted pin 32 having knurled knob 34 and screw shank 36 on which moves traveler nut 38. Pin 32 can rotate but can not move longitudinally in block 30; and, as it is rotated, it will cause nut 38 to move in whichever direction is dictated by the lead of the threads and the direction of rotation. A semi-rigid small rod or wire link 40 is connected between nut 38 and spirit level 26. By forming link 40 as a U-shaped loop and by properly selecting material of suitable resiliency, I can arrange that the rotation of screw 36 will accurately be translated into movement of nut 38 and a correlative tilting or rocking of the spirit level. In addition, the resiliency of U-shaped link 40 is such that at all times the link is tensioned to such a degree that any slack between the screw and nut threads is absorbed and lost motion is precluded. This makes it possible to avoid error during the transfer of a predetermined arrangement of the level from the patient's

mouth to a supporting device such as an articulator.

A supporting assembly for bite-table 18, such as could be used to mount it in an articulator or the like, is shown in Figures 1 and 5. This assembly is used to support the bite-table and to adjust the same to the plane it assumed in the patient's jaw by tilting the bite-table until spirit level 26 has the same reading. The center of bite-table 18 is bored to provide opening 42 which is encircled by interiorly threaded collar 44 on the under side of the table. This is for the purpose of detachably mounting the bite-table on a supporting column which may be supported by an articulator. The bite-table should be rockable on column 46. An exteriorly threaded stud 48 is positioned in opening 42 and has a bifurcated lower end that straddles fin 49 which is part of the column. A pivot pin 50 hingedly joins the stud to the column so that it may be rocked thereon. The length of the stud and the location of the pivot pin is such that, when the stud is properly joined to bite-table 18 by being threaded therein, the axis of pivot pin 50 coincides with median 19 and lies in the plane of the top of bite-table 18. This arrangement insures that when bite-table 18 is rocked the surface of the table will always coincide with the axis about which rocking takes place. Thus, with the center of the table positioned over the center of support column 46 and under the center of an upper support of an articulator, even though the bite-table is rocked the bite-plate will not be moved laterally away from its central position in the articulator.

Rocking of stud 48 on column 46 is obtained by means of moving lever arm 54 which is pivotally connected to stud 48 at one end. In the lower position of the column is journaled screw 56 having knob 58 and on which screw is moved traveler nut 60. Horn 62 on nut 60 extends upward and is pivotally connected to the other end of lever 54. Screw 56 is journaled in column 46 in a manner permitting rotary movement but not permitting longitudinal movement, so rotary movement of knob 58 is translated into longitudinal movement of traveler nut 60 and corresponding tilting of bite-table 18 through horn 62 and lever arm 54.

After spirit level 26 has been adjusted to a horizontal position while bite-plate 10 was positioned snugly on the patient's maxilla, bite-table 18 is positioned on column 46 and is tilted by means of adjustment of knob 58 until spirit level 26 again is in a horizontal position. At this point bite-plate 10 has the same lateral inclination regarding the horizontal as it assumed while in engagement with the patient's maxilla.

Articulator and associated parts

In the preparation of dentures according to my method, I prefer to use a Fournet-type articulator such as is shown in Figures 1 and 2. This articulator has a T-shaped base with a forwardly extending arm 70 and rearwardly located lateral arms, as 71. Foot 73 on front arm 70 has a vertical passage 75 for the reception of various appliances and thumb screw 74 intersects passage 75 to clamp the stems of appliances that may be therein inserted. The lateral arms, as 71, each have adjustable feet, as 83, which may be employed in leveling the articulator on a table or bench. As will be more apparent later, the articulator should be leveled so that column 46 will be truly vertical.

Rising from the juncture of arms 70, 71 is pillar 75 having a capping boss 77 on its upper end.

Upper arm 78 is bifurcated to straddle boss 77 and is pivotally connected thereto by pin 79. Leg 80 depends from arm 78 alongside the pillar and adjusting screw 81 passes through the pillar to establish and maintain desired right angularity between arm 78 and pillar 76. Locking screw 82 passes through the pillar and seats in leg 80 to prevent pivoting of arm 78 on occasion. At the forward end of arm 78 is a gudgeon 84 having its upright passage 85 intercepted by set screw 86 for the reception of mounting pins on appliances used in connection with the articulator. Such an appliance is shown in Figures 1 and 2 in which there is an upper mounting plate comprising shaft 88, hinge leaf 89 secured thereto at right angles, and hinged mounting plate 90 pivotally connected to hinge leaf 89 by pin 92. Mounting plate 90 has ports, not shown, for reception of plaster when a model is mounted thereon.

By placing the upper mounting plate in the articulator with its shaft locked in place in gudgeon 84 by screw 86 and attaching universal bubble level 94 on the upper end of shaft 88, it is possible through manipulation of the adjustable feet, as 83, to place the articulator in oriented position with passage 85 directly overlying passage 75. In this leveled adjustment appliances placed in arms 70 and 78 will be accurately superimposed. Universal level 94 has a lower socket 96 which fits snugly over the upper end of shaft 88 and includes a conventional glass faced, liquid filled chamber containing a small bubble that, when the device is level, seeks the highest point in the chamber and is visible from above.

In bisecting the intermaxillary space and other operations determining the proper occlusion of the denture, it is useful to have a visible outline of a horizontal plane in this area. To form this outline, I attach upstanding pins 100 to the arms of the articulator, as 70, 71, by connecting arms 102. The three pins 100 are at the apices of a triangle which I graphically establish by snapping rubber band 104 or a thread therearound. This triangle lies in a horizontal plane since the pins are scored in like manner to provide grooves for reception of the band or thread.

I have found that with slight preparation of models 14, 16 before mounting them in the articulator, the production of the dentures can be greatly facilitated. Each model has a flat base face 110 which is employed in mounting the same on the mounting plates. By placing the model flat on base plate 112, as shown in Figure 4, and employing the spiling means there disclosed I scribe thereon the spiling or guide line 114. The spiling means comprises the upright guide column 120 on which is pivotally and slidably mounted in carriage 122 which has outstanding finger 124 and scribing point 126. The spiling operation is performed by rotating model 14 on base plate 112 with point 126 in contact with the exposed face of the model and finger 124 riding on the crest or ridge representing in the model the upper bone line of the patient. It is important that point 126 be kept at right angles to the ridge being traced during the scribing of line 114.

Steps in preparing denture

After positioning upper bite-plate 10 on bite-table 18 with median lines 17 and 19 coinciding, as shown in Figure 3, bite-plate 10 is engaged with the patient's maxilla. The dentist, having first positioned the patient's head in a vertical position, adjusts spirit level 26 one way or the other through use of knob 34 until the bubble is centered. Transferring bite-table 18 to up-

right column 46, the table is adjusted by means of knob 58 until the bubble in spirit level 26 again indicates that a horizontal position has been reached. At this point, bite-plate 10 will have the same lateral inclination regarding the horizontal as it assumed while in position on the patient's maxilla. Bite-plate 10, as shown in Figure 1, has been oriented to this position. Model 14 is then positioned on bite-plate 10 and will assume the same transverse plane as the patient's maxilla. Model 14 is attached as by cement to the hinged and ported mounting plate 90 by means of plaster-of-Paris 130 which adheres to the flat face of the model and tends to exude through and mushroom over the edges of the openings or ports in mounting plate 90.

Bite-table 18 may then be removed and bite-plate 12 be temporarily joined with bite-plate 10 by fillets 132 which may be either utility wax or plaster as shown in Figure 2. Of course, the bite-plates will be locked together with their incisal portions in contact with the proper centric relationship established. Model 16 may then be positioned in fitting relation with bite-plate 12.

In this mounting arrangement, spiling lines 114 will be exposed to the dentist or technician, as seen in Figure 2, even though the bite-plates conceal the ridges of the model from view. Lines 114 serve as guides in the fore-and-aft tilting of the models in order that there may be a desired bisecting of the intermaxillary space between the crests of the jaws as an aid in the correct placement of teeth in the denture for proper chewing and other functions. Bearing in mind that upper model 14 is first only supported on plate 90 and that the hinge between plates 89 and 90 is still free, it will be seen that the models and bite-plate assembly can be readily tilted about a lateral axis represented by hinge pin 92.

With the spiling lines 114 visible and the horizontal plane established by band or thread 104, the technician views the articulator from the side and proceeds to tilt plate 90 relative hinge pin 92 until he has bisected the intermaxillary space as he desires. He then as shown in Figure 2 locks lower and upper mounting plates 89 and 90 together by fusing additional plaster 140 around and between them to immobilize the hinge. Thereupon, a lower mounting plate 142, such as is shown in dotted lines in Figure 2, can be placed under lower model 16 to support it when bite-plates 10 and 12 have been removed. The preparation of the dentures may thereafter proceed according to custom.

By the use of the structures and techniques that have been described it is possible to a normally careful technically trained person to provide a patient with very comfortable artificial dentures that are functionally inter-related, are very perfect functionally for mastication and have high esthetic characteristics. Also it is possible for the dentist to save much time in his work, to work with confidence that the outcome will be pleasing to the patient, and that he will not in the future have to devote much additional time to pacifying the patient or changing and adjusting the dentures to each other or to the patient's mouth. These to a professional man are highly desirable results and by their reflection in the attitude and satisfaction of the patient are much to be sought.

There has been described certain details of construction and operation and specific methods or techniques but it will be understood that

changes and modifications may be made by those skilled in the art to meet particular circumstances. It is therefore intended that such modifications and alterations as fall within the spirit and scope of the subjoined claims shall likewise be covered by this patent.

Having thus described my invention, I claim:

1. In the preparation of dental prosthetic devices, the method, comprising: scribing on the sides of models of a patient's maxilla and mandible lines corresponding to the profile of the ridges of the maxilla and mandible; forming a bite plate of the maxilla of the patient; placing said bite-plate in engagement with the patient's maxilla and determining the plane of occlusion laterally of the patient's head; placing said bite-plate under the upper supporting member of an articulator in the same plane of occlusion laterally of said articulator as the plane of occlusion determined in contact with said maxilla; positioning a model of the patient's maxilla on said maxilla bite-plate; pivotally connecting said maxilla model to said upper supporting member to pivot about a horizontal axis running transversely of said articulator forward of said model; securing a model of the patient's mandible to said maxilla model with their incisal portions in contact in proper occlusal relationship; swinging said models about said horizontal axis until a position of desired division of intermaxillary space has been reached by reference to said scribed maxilla and mandible ridge lines; and then securing said maxilla model fixedly to said upper supporting member by immobilizing the pivotal connection.

2. In the preparation of dental prosthetic devices, the method, comprising: forming a bite-plate of the maxilla of the patient; placing said bite-plate in engagement with said maxilla and determining the plane of occlusion laterally of the patient's head; placing said bite-plate under the upper supporting member of an articulator in the same plane of occlusion laterally of said articulator as the plane of occlusion determined in contact with said maxilla; positioning a model of the patient's maxilla on said maxilla bite-plate; pivotally connecting said maxilla model to said upper supporting member to pivot about a horizontal axis running transversely of said articulator forward of said model; securing the model of the patient's mandible relative to said maxilla model with their incisal portions located in proper occlusal relationship; swinging said models about said axis until a position of proper fore-and-aft division of intermaxillary space has been reached; and then securing said maxilla model fixedly to said upper supporting member by immobilizing the pivotal connection.

3. In the preparation of dental prosthetic devices, the method, comprising: scribing on the sides of models of a patient's maxilla and mandible lines corresponding to the profile of the ridges of the maxilla and mandible; orienting the model of the patient's maxilla under an upper supporting member of an articulator in the same plane of occlusion laterally of said articulator as the plane of occlusion of the patient's maxilla laterally of the patient's head; pivotally connecting said model to said upper supporting member to pivot about a horizontal axis running transversely of said articulator forward of the model; securing the model of the patient's mandible to said maxilla model with their incisal portions in contact in proper occlusal relationship; establishing a visible outline in a horizontal

plane in the intermaxillary region; swinging said models about said axis until a position of desired division of intermaxillary space has been reached by reference to said scribed maxilla and mandible ridge lines and said visible outline; and then securing said maxilla model fixedly to said upper supporting member by immobilizing the pivotal connection.

4. In the preparation of dental prosthetic devices in which a model of the patient's maxilla is to be positioned on an upper supporting member of an articulator, the method comprising: forming a bite-plate of the upper jaw of the patient and providing the same with a generally flat lower exterior surface, disposing the patient's head in a vertical position relative a vertical plane passing from front to back of the head, placing the bite-plate in the patient's mouth on the maxilla and determining the lateral relation of the flat portion of the bite-plate to a true horizontal, supporting said bite-plate by said flat surface and locating the bite-plate in the articulator adjacent an upper supporting member with the flat surface in the same lateral relation to the true horizontal as the flat surface of the bite-plate occupied in the patient's mouth, whereby the model of the maxilla relating to said bite-plate may be placed in the bite-plate and attached to the upper supporting member in actual simulation of the lateral orientation of the patient's maxilla.

5. In the preparation of dental prosthetic devices in which a model of a patient's maxilla is to be joined to an upper supporting member of an articulator, the method comprising: placing a bite-plate on the maxilla, disposing the patient's head in a vertical position relative a vertical plane passing from front to back of the head, determining the lateral relation of the bite-plate to true horizontal, locating said bite-plate in an articulator adjacent the upper supporting member thereof and in the same lateral relation to true horizontal as the bite-plate occupied in the patient's mouth, positioning the model relating to said bite-plate in said bite-plate and beneath said upper supporting member of the articulator, and attaching said model to said upper supporting member of the articulator.

6. In the preparation of dental prosthetic devices, the method, comprising: orienting a model of a patient's maxilla under an upper supporting member of an articulator in the same plane of occlusion laterally of said articulator as the plane of occlusion of patient's maxilla laterally of the patient's head; pivotally connecting said model to said upper supporting member to pivot about a horizontal axis running transversely of said articulator forward of the model; securing a model of the patient's mandible to said model of the maxilla with their incisal portions associated in proper occlusal relationship; swinging said models about said axis until the position of desired division of intermaxillary space has been reached; and then securing said maxilla model fixedly to said upper supporting member.
